WEANER

Charles H. Patterson, Shelton, Wash.

Application August 8, 1952, Serial No. 303,263

1 Claim. (Cl. 119—131)

1

This invention relates to new and useful improvements and structural refinements in calf and colt weaners and the principal object of the invention is to provide a weaner having a closure member swingable between operative and inoperative positions and means for automatically locking the closure member in its operative position when the calf or colt raises its head to nurse. However, when the animal lowers its head to graze, the locking means are automatically released and the closure member assumes its inoperative position.

Specifically, the instant invention is an improvement on the device disclosed in my Patent No. 1,303,587 which was granted to me on May 13, 1919. After working with the weaner constructed in accordance with my prior patent, I found that the closure locking means lend themselves to structural and functional improvements such as are embodied in the instant device.

Some of the advantages of the invention reside in its simplicity of construction, in its efficient operation, in its durability and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a side elevational view of the invention in position on an animal's head, the latter being raised;

Figure 2 is a side elevational view, similar to that shown in Figure 1, but with the head lowered;

Figure 3 is a front view of the invention per se;

Figure 4 is a sectional view, taken substantially in the plane indicated by the line 4—4 in Figure 3, and

Figure 5 is a perspective view of the closure member used in the invention.

Like characters of reference are employed to designate like parts in the specification and throughout the several views.

Referring now to the accompanying drawing in detail, the weaner is designated generally by the reference character 10 and embodies in its construction a hollow, muzzle receiving body 12 which is preferably formed from resinous plastic material and is provided with a front opening 14. The body 12 is sustained in position on the head of an animal by suitable harness 16.

A closure for the opening 14 consists of a sub-

stantially U-shaped member 18 which is also preferably formed from resinous plastic material and includes a convex, closure forming bight portion 18a and a pair of side pieces 20, 22.

The side pieces 20, 22 are attached by coaxial pivot elements 24 to the opposite sides of the body 12 so that the closure member 18 may be swung from its operative position, as shown in Figures 1, 3 and 4 to its inoperative position shown in Figure 2. The closure member 18 is gravity-responsive and a substantially U-shaped bar 26 is secured to the closure member by means of the aforementioned elements 24 and by means of additional elements 28 to assure positive swinging movement of the closure member in response to the effect of gravity.

It will be apparent from the foregoing that when the animal's head is lowered as shown in Figure 2, such as for example while grazing, the weight of the bar 26 will sustain the closure member 20 in its open position, leaving the opening 14 uncovered. However, when the animal raises its head to nurse, the combined weight of the closure member 18 and the bar 26 will automatically swing the closure member to its operative position, covering the opening 14.

Means are provided for automatically locking the closure member in its operative, closed position, these means involving the provision of an outwardly offset portion 30 intermediate the ends of the side piece 20 and a hook 32 is pivotally mounted in this offset portion by means of a pivot element 34. When the head of the animal is raised and the member 18 is in its closed position, the hook 32 lockably engages a laterally projecting detent 36 on a side of the body 12, so as to prevent the closure member 18 from being opened. However, when the animal lowers its head, the hook 32, in response to gravity, automatically becomes disengaged from the detent 36 and opening of the closure member is facilitated.

It will be observed that when the closure member 18 is in its operative position, the convex configuration of the bight portion 18a provides a vent 38 in communication with the top of the opening 14 in the body 12, so as to facilitate breathing. (See Figure 4.) Moreover, a flange 12a at the bottom edge of the opening 14 in the body 12 abuts the lower edge of the bight portion 18a, so as to afford a stop for the closure member in its operative position. Excessive opening movement of the closure member is prevented by the engagement of the bar 26 with the underside of the body 12, as shown in Figure 2.

It is believed that the advantages and use of

the invention will be clearly understood from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

In a weaver, the combination of a muzzle-receiving body provided at the front thereof with 15 an opening, a gravity-responsive closure for said opening comprising a substantially U-shaped member including a closure-forming bight portion and a pair of side pieces, coaxial pivots attaching said side pieces to the opposite sides of 20

5 said body whereby the closure member is swingable between operative and inoperative positions relative to the body, one of said side pieces being provided intermediate the ends thereof with an outwardly offset portion, a gravity-responsive locking hook disposed within the offset portion of the associated side piece and depending therefrom, and a detent projecting from a side of said body and engageable by said hook when said closure member is in its operative position.

CHARLES H. PATTERSON.
